UNITED STATES PATENT OFFICE.

EDWARD C. BACHERT, OF CANTON, OHIO.

COMBINED MATCH-BOX AND HOLDER.

SPECIFICATION forming part of Letters Patent No. 472,022, dated April 5, 1892.

Application filed February 4, 1891. Serial No. 380,115. (No model.)

To all whom it may concern:

Be it known that I, EDWARD C. BACHERT, a citizen of the United States, residing at Canton, in the county of Stark and State of Ohio, 5 have invented certain new and useful Improvements in a Combined Match-Box and Holder; and I do hereby declare that the following is a full, clear, and exact description of the same, reference being had to the annexed drawings, making a part of this specification, and to the letters of reference marked thereon, in which—

Figure 1 is a perspective view. Fig. 2 is a perspective view showing a slight modification and the top or upper part broken away. Fig. 3 is a back view of the match-box holder. Fig. 4 is a view of one side of the holder, showing a slight modification. Fig. 5 is a view of the blank, showing the same cut or 15 formed to be folded to form the match-box. Fig. 6 is back view showing a piece of paste-board or other material placed in the back of the match-box for the purpose of closing the back of the holder proper. Fig. 7 is a view 20 showing one of the retaining-grooves and a stop. Fig. 8 is a view of a portion of the retaining-groove, showing the holding cap or lip. Fig. 9 is a transverse section through line $z z$, Fig. 3. Fig. 10 is a transverse section of one of the retaining-grooves, showing 25 the location of one of the stops. Fig. 11 is a transverse section through line $X' X'$ of Fig. 1.

The present invention has relation to a combined match-box and holder; and it consists 30 in the different parts and combination of parts hereinafter described, and particularly pointed out in the claims.

Similar letters of reference indicate corresponding parts in all the figures of the drawings.

In the accompanying drawings, A represents the blank from which the match-box is formed, said blank being preferably of metal. 45 The parts of the blank A extending beyond the lines $a a$ and $b b$ are bent substantially at right angles to the balance of said blank A, the bends being made on the lines $a a$ and $b b$. The bends of the blank A on lines $a a$ and $b b$ form the front sides B and the backs 50 C. The blank A is again bent on the lines c

c and $d d$, which bends form the vertical sides D. For the purpose of forming the grooves E the portions F of the blank A are bent on the lines $z z$, after which a second bend is 55 given to the portions F, thereby completing the grooves E.

For the purpose of providing a means for uniting the top of the match-box holder the extensions G are provided, which extensions 60 are united by means of the folds H, substantially as illustrated in Fig. 11, or, if desired, said extensions G may be formed long enough to lap one over the other and be securely attached together by solder or rivets. 65

It will be understood that the extensions G may be attached together in any convenient and well-known manner without departing from the nature of my invention.

The grooves E are for the purpose of holding the sand-paper I, which is preferably located in the position illustrated in Figs. 3 and 4. For the purpose of preventing the sand-paper I from descending to the bottom of the match-box the stops J are provided, which 70 stops are located so as to hold the bottom of the sand-paper I. The stops J are formed by cutting the raw edge of the metal forming the grooves E, again cutting at right angles to the first cut, thereby forming the lips or 75 stops J.

When it is desired to close the back of the match-box holder, the card K or its equivalent is placed in the position illustrated in Fig. 6, which card extends the entire length 80 of the match-box holder. It will be understood that when cards—such as K—are used, the stops J are to be dispensed with, which may be done by bending or leaving said stops in line with the metal-forming grooves E. 85

It will be understood that any kind of material may be used to form the cards K, and, if desired, the portion of the card extending above the sides D may have printed upon them any desired kind of advertising. If desired, the sand-paper I may be dispensed with and a card substituted therefor. 90

For the purpose of securely holding the sand-paper I or its equivalent in proper position and to prevent the same from becoming 95 accidentally displaced the lips K' are provided, which lips are originally formed upon 100

the portion F of the blank A, as illustrated in Fig. 5. After the card or sand-paper has been properly adjusted the lips K' are bent down over the top or upper ends of the 5 grooves E, as illustrated in Fig. 3.

In Fig. 4 a slight modification is shown, which consists in only extending the grooves E to a point near the top or upper ends of the sides D. For the purpose of making the 10 match-box holder more rigid the flanges or ribs e may be pressed or formed upon the back of the match-box holder. For the purpose of providing a means for hanging the match-box holder the aperture f is provided, which 15 is preferably formed by punching after the extensions G are united together. When it is desired to use my device as a match-box holder, the tray g is placed in the position illustrated in Fig. 1.

20 When it is desired to use my device as a match-box, the card K is placed in the position illustrated in Fig. 6 and the matches placed between the sides B and the card or back K.

25 For the purpose of removing the matches from the tray g or the box proper the opening A' is provided by so forming the sides B that their edges will not meet. For the purpose of providing a means for holding the sides B 30 and the backs C the flanges a' are formed and are bent or folded against the sides and

backs, substantially as illustrated in the drawings.

Having fully described my invention, what I claim as new, and desire to secure by Letters Patent, is—

1. In a match-box holder formed from the blank A, the combination of the front sides B, separated by an oblong opening A', the sides D, provided with the vertical grooves 40 E, the backs C, the flanges a', and the tray g, substantially as described.

2. The combination of the front sides B, the vertically-grooved sides D, the backs C, and the flanges a', formed from a single blank, 45 substantially as described.

3. The combination of the front sides B, separated by an oblong opening A', the sides D, having grooves E, provided with lips K', the backs C, and the flanges a', substantially 50 as described.

4. The combination of the front sides B, the backs C, and the sides D, having vertical grooves E, provided with stops J, substantially as described.

55 In testimony that I claim the above I have hereunto subscribed my name in the presence of two witnesses.

EDWARD C. BACHERT.
